CURTAIN SUPPORT

Charles P. Henry, Cranston, R. I., assignor to
James N. Henry, Providence, R. I.

Application July 16, 1936, Serial No. 90,906

5 Claims. (Cl. 156—19)

My invention relates to curtain supports.

Heretofore such structures, which usually extend in front of and across a window or door, were liable, because of the force of the incoming air through an open upper portion of the window, or because of a draft through the opening of the door, to cause a rattling of the curtain or drapery suspension rings, and a bulging of the curtain.

Certain objects of the present invention are to prevent the rattling of the rings; to diminish the derangement of the depending curtain by the air or otherwise; to effect these objects without obscuring any pattern borne by the latter, and by a guarding means agreeable to the eye. Further objects are strength and inexpensiveness of construction.

With the above and other objects and advantageous features in view my invention consists in the novel arrangement of parts more fully disclosed in the following description and drawings, and more specifically defined in the claims.

In the accompanying drawing,

Figures 1 and 2 are a front elevation and a top plan view respectively of a curtain support embodying my invention.

Figure 3, an end elevation of the same, including a curtain attached thereto, the curtain and a portion of the support being shown in section on a line corresponding to line 3—3 of Figure 1.

30 Figure 4, a rear end view of the supporting arm, and

Figure 5, a perspective view of the bracket.

Like reference characters indicate like parts throughout the views.

35 In the drawing a curtain supporting member 9 includes a horizontally disposed arm 10 integral with the inner end of which is a pivot finger 11. A rearwardly and upwardly inclined lateral lug 12 is integral with the outer end of the arm 10 and carries a horizontal telescoping shaft member, represented in a general way by the reference numeral 13, comprising an inner rod section 14 integral at its inner end with the offset lug 12, a tubular outer rod section or sleeve 15 of greater 40 length than the section 14 provided with a longitudinal slit 16, and slidable with a degree of friction upon the inner section; and a closure member for the free end of the outer section consisting of a shank portion 17 embraced in the latter, and an ornamental head portion 18. In this instance the shaft member 13 is transversely rectangular.

45 Cast integral with the lower portion of the arm 10 and with the portion of the side of the latter opposite from the lug 12, is an outwardly and downwardly directed guard plate 20 which is,

as evident in Figures 3 and 4, forwardly offset somewhat relatively to the pivot member 11, and having its upper edge 21 located diagonally in front of and below the shaft member 13, with which it is parallel and from which it is interspaced. The plate 20 is provided with openings or interstices 23 constituting portions of superficial ornamentation but purposed primarily for admitting a partial view of a curtain or drapery 5 24, which is suspended upon the shaft member, 10 in this instance by slidable rings 26 and connecting rings 27.

A bracket member 29 comprises an attaching plate 30 with spaced, forwardly directed flat arms 31 having vertically aligned perforations 32 to 15 receive the finger 11 which pivots therein. Holes 34 in the plate 30 receive attaching screws 35 for engagement in the window frame or door frame 36.

The rearwardly offset relation of the shaft 20 member 13 relatively to the guard plate 20 affords a resultant space 37 therebetween to accommodate a curtain looped upon the shaft member 13, or curtain supporting rings 26, when rings are employed as an auxiliary suspension means. The 25 slight forward offset of the guard plate also contributes to the space 37.

The downwardly directed disposition of the ornamental guard plate 20 relatively to the shaft member 13 is important as it prevents any forward swelling of the upper portion of the curtain by reason of any draft moving transversely of the curtain emanating from either an open window or door.

The described curtain support lends itself to ornate and inexpensive ornamentation, and possesses maximum strength because its entire construction, excepting the slidable tubular shaft extension section is capable of being cast.

40 I claim:—

1. In a curtain support, a horizontally disposed arm, a pivot element upon the arm, a rearwardly directed lateral lug upon the arm, a depending guard plate integral with the front of the arm, and a horizontal shaft member integral 45 at its inner end with the lug and parallel with the guard plate.

2. In a curtain support, a horizontally disposed arm, a pivot element upon the arm, a shaft member supported by the arm, and a guard plate upon the arm disposed in a vertical plane 50 distinct from the vertical plane of the shaft member.

3. In a curtain support, a horizontally disposed arm, a pivot element upon the arm, a guard 55

plate upon the arm, and a horizontally disposed shaft member supported by the arm behind the guard plate.

4. In a curtain support, a guard plate adapted to be vertically positioned, means for supporting said guard plate comprising an arm and a bracket engageable element, a shaft member, and means for mounting said shaft member behind and above

said plate and generally parallel thereto and spaced therefrom.

5. In a curtain support, a guard plate adapted to be vertically positioned, an arm secured to said plate and having a pivot element, a lug extending rearwardly of the plate, and a shaft secured to said lug and extending parallel to said plate.

CHARLES P. HENRY.
